UNITED STATES PATENT OFFICE.

FRANK SCHILZ, OF MILWAUKEE, WISCONSIN, ASSIGNOR TO HUGO LOEWEN-BACH, OF MILWAUKEE, WISCONSIN.

PAPER HOLDER AND FOLDER.

SPECIFICATION forming part of Letters Patent No. 687,343, dated November 26, 1901.

Application filed October 9, 1900. Serial No. 32,496. (No model.)

To all whom it may concern:

Be it known that I, FRANK SCHILZ, a citizen of the United States, residing at Milwaukee, county of Milwaukee, and State of Wisconsin, have invented new and useful Improvements in Paper Holders and Folders, of which the following is a specification.

My invention relates to improvements in paper holders and folders, and pertains especially to that class of paper-holders used for toilet-paper, in which the withdrawal of one sheet of paper causes a partial discharge of the next, thus permitting all the sheets to be withdrawn by pulling on the exposed portion of each sheet as it projects from the holder.

The objects of my invention are, first, to provide a more efficient and reliable means for communicating motion from each sheet to partially discharge the next; second, to provide means whereby the sheets are folded while being discharged, and, third, to provide a form of construction in which it will not be necessary to bind the package of sheets together.

In the following description reference is had to the accompanying drawings, in which—

Figure 1 is a front view of my invention. Fig. 2 is a similar view, partially broken away, to show the arrangement of the feed-rollers. Fig. 3 is a vertical longitudinal sectional view of the same. Fig. 4 is a detail view showing the feed-roller and rotating guide geared together.

Like parts are identified by the same reference-letters throughout the several views.

An inclosing cabinet A is provided with a transverse slot B in its front wall at or near its longitudinal center. Within the cabinet I have provided a feed-roller C, located in proximity to the slot and parallel thereto, with an opposing-guide D preferably slightly separated from the roller C, so as to leave a narrow opening between the guide and roller, through which the paper is fed to the slot. The guide D preferably consists in a roller similar to the roller C and arranged to run idle by frictional contact with the paper, although it may, if desired, be driven from the roller C by suitable gearing, as shown in Fig. 4, or it may be located in contact with the

roller C and driven directly therefrom. A third roller E is located above the roller C and connected with the latter by rubber belts F or other suitable motion-transmitting connections. The rollers are surfaced with sandpaper or other frictional material, although if the guide D is made stationary it should be smooth-surfaced to avoid friction thereon.

A package G of unbound paper sheets is placed on end within the cabinet and held in position by means of a pressure-plate H, which is slidably mounted by means of laterally-projecting studs I in diagonal guides J, whereby the plate is permitted to move downwardly and forwardly against the paper, the plate being of sufficient weight to produce the requisite pressure of the paper against the rollers.

The rear wall K of the cabinet is made removable and is adapted to be normally held in position by a locking-rod L, which passes through the side walls of the cabinet and retaining-loops M on the rear wall.

An actuating-knob is N preferably secured to the roller C and projects from the cabinet in a position to be grasped by the user to facilitate starting the first sheet.

Q represents ribs or flanges projecting inwardly from the respective side walls of the cabinet and adapted to fit counterpart recesses in the paper, thus making it necessary to adjust the sheets properly in order to insert them in the cabinet. These ribs or flanges also serve to support the paper and prevent it from being crowded downwardly to the lower part of the cabinet by the pressure-plate.

The ribs Q do not extend to the rollers, but are terminated at such a distance from the vertical plane of the rollers as to leave the front sheet or sheets of the package of the paper unsupported. Otherwise these ribs would interfere with the withdrawal of the front sheet.

On turning the knob motion is communicated from the roller C to the front sheet of paper by frictional contact and to the roller E through the medium of the belts F. As the roller C and guide D revolve in opposite directions, the paper in contact therewith will be folded and fed through the slot between them, as shown in Fig. 3. The sheet may then be

grasped and pulled out, when the final movement of the roller, together with the frictional contact of the withdrawn sheet, will cause the next sheet to fold and be sufficiently discharged to expose the folded edge in a position to be grasped and withdrawn. The entire package may thus be withdrawn in successive sheets without further recourse to the knob.

10 The roller E facilitates the discharge of the second sheet, as it will come in direct contact therewith as soon as the end of the first sheet passes below it. This roller may, however, be dispensed with, if desired; but the paper must then be fed out by means of the knob, as the use of the third roller E is essential if it is desired to have the second sheet fed out sufficiently to be grasped by the operator during the withdrawal of the preceding sheet.

15 The reason for this is that the roller E serves as a starter for the second sheet as it comes in contact with such sheet, while the preceding sheet is still in contact with the rollers C and D, which are actuated thereby, and as the roller E is driven from the roller C it is obvious that the upper portion of the second sheet will be pushed downwardly and drawn in between the rollers C and D and between the ends of the preceding sheet, so that when

20 such preceding sheet is entirely removed the folded edge of the next succeeding sheet will project through the slot B; but the construction shown, being more efficient and reliable, is preferred.

25 35 Having thus described my invention, what

I claim as new, and desire to secure by Letters Patent, is—

1. The combination with a suitable receptacle, provided with a slot in one of its walls; a set of three rollers mounted in the interior of said receptacle, in proximity to said slotted wall, two of said rollers being located on one side of said slot, and having driving connections with each other, and the third roller being located on the opposite side of the slot from that occupied by the other two; together with means for supporting sheets of paper in contact with said rollers.

2. The combination with a suitable receptacle having a set of three rollers, located in proximity to one of the walls of said receptacle, and a slot in said wall; two of said rollers being located on one side of said slot and having driving connections with each other, and the third roller being located on the opposite side of the slot from that occupied by the other two; means for supporting sheets of paper in contact with the rollers; and paper-supporting ribs or flanges extending along the side walls of the receptacle to points near the plane of the rollers, but terminating at such a distance from the rollers, as to leave the front sheet of paper unsupported by said ribs or flanges.

In testimony whereof I affix my signature in the presence of two witnesses.

FRANK SCHILZ.
